CLAIM

The ornamental design for a razor handle, as shown and described.

DESCRIPTION

FIG. 1 is a perspective view of an embodiment of the razor handle.

FIG. 2 is a back view thereof.

FIG. 3 is a front view thereof.

FIG. 4 is a left side view thereof.

FIG. 5 is a right side view thereof.

FIG. 6 is a top view of thereof; and,

FIG. 7 is a bottom view of thereof.

The evenly spaced broken lines in the drawings are used to illustrate the environment and form no part of the claimed design. The dash-dot-dash broken lines illustrate the bounds of the claim and form no part of the claimed design.

1 Claim, 4 Drawing Sheets(56)
